UNITED STATES PATENT OFFICE.

CLARENCE S. JOHNSON, OF FREDERICK, MARYLAND, ASSIGNOR OF ONE-HALF TO
H. R. SNOOK, OF FREDERICK, MARYLAND.

BOTTLE CAPPER.

1,408,354.

Specification of Letters Patent. Patented Feb. 28, 1922.

Application filed October 11, 1921. Serial No. 506,945.

To all whom it may concern:

Be it known that I, CLARENCE S. JOHNSON, a citizen of the United States, residing at Frederick, in the county of Frederick and 5 State of Maryland, have invented certain new and useful Improvements in Bottle Cappers, of which the following is a specification.

This invention relates to bottle cappers 10 and more particularly to hand operated devices of this character.

The object of the invention is to provide a bottle capper so constructed as to permit of its being quickly adjusted for capping 15 bottles of different heights.

Another object is to provide a device of this character composed of relatively few parts arranged so as to be effective in operation, cheap to manufacture, not easy to 20 break and capable of being folded compactly when not in use.

With these and other objects in view, the invention consists in certain novel features of construction as hereinafter shown, described and claimed.

In the accompanying drawing:

Figure 1 represents a side elevation of the capper constituting this invention the parts being shown in full lines for use in 30 connection with tall bottles and in dotted lines for use in connection with short bottles; and

Fig. 2 is a top plan view thereof.

In the embodiment illustrated a suitable 35 base 1 is provided equipped with a suitable bottle holding portion 2 preferably shaped as shown and having a curved rib 3 of suitable shape to aid in retaining the bottle on the base. The rib 3 is preferably made in- 40 tegral with the base 1 and said base is also equipped with radially extending apertured ears 4 for securing it to a support. An integral boss 5 is arranged between one of the ears 4 and the periphery of the base 1 car- 45 ries a standard 6. This standard 6 may be either fixedly or removably mounted on the boss 5 being here shown removable by means of set screw 5' to facilitate the separation of the parts for storing them in a small space.

50 The standard 6 is substantially T-shaped in cross section and the upper end 7 thereof is off-set inwardly with a shoulder 8 formed at its inner end for a purpose presently to be described.

55 The ribs 9 extend along the inner edge

of the lower portion 6 of the standard and along the outer edge of the upper portion 7 thereof said ribs operating as reinforces for the standard at the lower portion thereof and at the upper portion as guides for the 60 capping member presently to be described. The front edge of the upper portion 7 of the standard is equipped with a plurality of teeth forming a rack 10 along said edge and which is designed to cooperate with the actuating member of a capper member pres- 65 ently to be described.

A capper carrying member 11 is mounted to slide on the rack portion 7 of the standard 6 and is shown constructed of a single sheet 70 of metal folded longitudinally and shaped to conform to the shape of the member 7 of the standard so that it will slide freely thereon, the ribs of said member 7 operating as guides for the member 11. Extending in 75 parallel relation from the sliding portion 12 of the member 11 on opposite sides of the member 7 are two plates 13 and 14 between which is fulcrumed midway their length a handle member 15 which carries at its inner 80 end a head 16 mounted to swing between the plates 13 and 14 on a pivot 18 which is spaced sufficiently distant from the teeth 10 of the rack so that the teeth 18^a of head 16, which are of suitable size and shape to mesh 85 with the teeth of the rack 10, may be thrown entirely out of engagement with the teeth of the rack by swinging the handle 15 to or past a vertical position thus permitting of readily adjusting the position of the 90 member 11 relative to base 1 by merely lifting or lowering handle 15 and its attached parts to permit of the teeth 18^a of head 16 being swung into engagement with the teeth of the rack at such point as is desired to 95 bring the capper 20 carried by the member 11 to the appropriate height for capping a particular bottle or to adjust it to a different height.

The capper 20 is chambered to receive the 100 cap to be applied to the bottle and has a shank 19 which is made flat and of a width or thickness to fit between the plates 13 and 14 and which is secured by a bolt 21 passing transversely through said plates and through 105 an aperture in the shank 19.

The plates 13 and 14 extend at one end longitudinally beyond the member 12 which slides on member 7 of the standard and the opposite ends of these plates are provided 110

with registering apertures for the reception of the bolt 21 which is employed for connecting the capper 20 with the member 11. The apertures in the ends of the plates 5 which lie flush or in transverse alinement with the end portion of the slide 12 are designed to receive the capper 20 when the device is to be used in connection with tall bottles. When it is to be used with shorter 10 bottles the member 11 is reversed on the shank portion 7 as is shown clearly in dotted lines in Fig. 1 and the capper 20 is engaged with this reversed end by passing the fastening screw 21 through the aperture 22 in the 15 extension of the plates 13 and 14 and through the shank 19 of the capper which is mounted between said plates as shown clearly in dotted lines in Fig. 1. The member 12 is limited in its downward movement 20 by engagement with the stop shoulder 8 on standard 6.

In the use of this capper a bottle is placed on the base 1 as shown in dotted lines in Fig. 1 and the cap to be applied to the bottle 25 is forced firmly onto the mouth of the bottle by the capper 20 as the handle 15 is swung downward, the teeth 18^a meshing with the teeth of the rack.

By tilting the handle 15 to or past a vertical position the teeth 18^a of the head 16 may be thrown out of mesh with the teeth of the rack and the member 11 may be then 30 freely moved up and down on the portion 7 of the standard 6 and if desired may be taken off and reversed to bring it in the dotted line position shown in Fig. 1 for use 35 in connection with short bottles. When this handle is so swung into vertical position the parts attached thereto may be entirely removed from the standard 6 to permit of 40 storing or shipping the device in compact disassembled but associated relation.

From the above description it will be obvious 45 that the gist of this invention resides in the peculiar construction of the member 11 to provide for its reversibility to adapt it for use in connection with tall or short bottles.

The formation of the member 11 from a 50 single piece of sheet metal provides a simple and cheaply constructed member of this

character and also one which is strong and durable.

The preferred embodiment of the invention is disclosed in the drawings and set 55 forth in the specification, but it will be understood that any modifications within the scope of the claimed invention may be made in the construction without departing from the principle of the invention or sacrificing 60 any of its advantages.

I claim:—

1. In a bottle capper, the combination of a standard having a rack portion, supporting means for said standard, a capper carrying member slidably mounted on said rack portion and including a pair of laterally spaced plates, a handle pivotally mounted between said plates midway their ends and having a segmental toothed head on the inner end thereof adapted to be thrown into or out of engagement with the rack, said member having capper receiving means at its opposite ends on opposite sides of said handle. 75

2. In a bottle capper, the combination of a base shaped to receive a bottle, a standard rising from said base, and having an up-standing rack portion inwardly off-set from the body portion thereof and provided at 80 its inner end with a stop shoulder, a capper member slidably mounted on said rack portion and composed of a sheet metal plate folded longitudinally intermediate its width, the folded portion being shaped to conform 85 to the rack portion and slidable thereon, a handle member arranged between the free edges of said plate and pivotally connected therewith midway the length of the plate, said handle having a head projecting inwardly and provided with teeth to cooperate 90 with the teeth of the rack for raising and lowering the sliding member on the operation of the handle, and a capper removably mounted on said sliding member and adapted to be carried by either end thereof to 95 provide for the use of the device in connection with either tall or short bottles.

In testimony whereof, I affix my signature hereto.

CLARENCE S. JOHNSON.
